[57] CLAIM

The ornamental design for a wristwatch, as shown and described.

DESCRIPTION

FIG. 1 is a front elevational view of a wristwatch showing my new design;

FIG. 2 is a right side elevational view;

FIG. 3 is a left side elevational view;

FIG. 4 is a rear elevational view;

FIG. 5 is a top plan view;

FIG. 6 is a front elevational view of another embodiment of my new design of FIGS. 1-5, all other views are identical to FIGS. 2-5 respectively.
